UNITED STATES PATENT OFFICE.

ANDERS H. ANDERSEN, OF POUGHKEEPSIE, NEW YORK.

DESIGN FOR A CLASS RING.

Application filed January 27, 1926. Serial No. 16,306. Term of patent 14 years.

To all whom it may concern:

Be it known that ANDERS H. ANDERSEN, a citizen of the United States, residing at 55 Market Street, in the city of Poughkeepsie, in the county of Dutchess and State of New York, has invented a new, original, and ornamental Design for Class Ring, of which the following is a specification, reference being had to the accompanying drawing, forming part thereof.

Figure 1 is an edge view, Figure 2 is a side view, and Figure 3 is a top plan view developed on a plane of the class ring constituting the new design.

I claim—

The ornamental design for a class ring as shown.

ANDERS H. ANDERSEN.
